Primary Examiner — Karen E Eldridge Powers(74) *Attorney, Agent, or Firm* — Gloria Tsui-Yip, Esq.; Gottlieb, Rackman & Reisman, P.C.(57) **CLAIM**

The ornamental design for a brush, as shown and described.

DESCRIPTION

FIG. 1 is a perspective view of my new design; FIG. 2 is a left side elevation view thereof; FIG. 3 is a top plan view thereof; FIG. 4 is a right side elevation view thereof; FIG. 5 is a bottom plan view thereof; FIG. 6 is a front elevational view thereof; and, FIG. 7 is a rear elevational view thereof. The broken-line showing of brush tips and bristles in the figures illustrates environmental structure that forms no part of the claimed design.
